UNITED STATES PATENT OFFICE.

BENJAMIN BODELL, OF AUBURN, NEW YORK.

STOP-MOTION FOR SPINNING-JENNIES.

SPECIFICATION forming part of Letters Patent No. 499,280, dated June 13, 1893.

Application filed November 8, 1892. Serial No. 451,320. (No model.)

To all whom it may concern:

Be it known that I, BENJAMIN BODELL, of Auburn, in the county of Cayuga, in the State of New York, have invented a new and useful Improvement in Stop-Motions for Spinning-Jennies, of which the following is a specification.

This invention relates to a spinning machine in which is employed a stop motion consisting of a lever suitably secured to the spinning frame and connected by a cord which passes through suitable devices and is connected with a spring to a belt shifter; when the machine is in operation the lever is in a vertical position and leaning against the strand or cord spun or being spun and is held in that vertical position by the cord unless the cord breaks in which case the lever is then pulled down and the belt is shifted from the tight pulley to the loose pulley, thus stopping the machine.

My invention consists in an improved lever composed of three essential parts, namely, a main lever rod, a tubular piece or sleeve which fits snugly over the main rod and a spring which is inserted in the tubular portion and keeps it at the required height above the cord or strand being spun. The tubular portion is provided with two vertical slots and a pin passing transversely through said slots and through the main rod within securely holds together the main rod, tubular portion and the spring within it and prevents the spring from pressing the tubular portion of the lever off the main rod. The slots in the tubular portion of the lever are of sufficient length to allow the operative to press down the tubular portion of the lever until it passes under the cord or strand being spun and up on the opposite side thereof. The lever will spring up above the strand or cord on the opposite side when the hand is removed. The lever now in use is one solid rod or piece. When the cord or strand being spun breaks the lever is drawn down as above stated, the strand is tied together and it is then necessary for the operative to hold up the cord or strand with one hand while he passes the lever rod under and to the opposite side of it. It requires time and two hands to do this and the cord often cuts or burns the fingers of the opera-

tive. It is to obviate these difficulties that I have invented my improvement.

In the accompanying drawings which form a part of this specification, Figure 1, represents a section of a spinning frame with a lever secured thereto which embodies my improvement, the lever being in position and held upright by the thread or strand as when the machine is in operation. Fig. 2 is an elevation of the lever containing my improvement—the dotted lines showing the position assumed by the lever when the thread breaks and the method of placing the lever back into position after the thread is tied. Fig. 3 is a detail view of the belt shifter; and Fig. 4 is a face view of a spinning jenny with my improvement applied.

Similar letters of reference indicate corresponding parts in all the figures.

The belt shifter *l* is pivoted at *l'* on the bar *S* and is pulled in one direction by the spring *n*—attached to said shifter below the pivot and to the hook screw *o*—passed through the nut *p*. The cord *h*—is fastened to the belt shifter and is passed over the pulley *k'* on the bracket *i'*—and the pulley *k*—on the bracket *i*—and its end is fastened to the eye *h'* on the main rod *B*.

A' represents part of the frame of a spinning jenny. *a*—represents the cord or strand being spun.

B is the main rod of the lever, and *C* is the top of the lever, part of which is tubular and fits snugly like a sleeve over the top of main rod *B*.

D—is a spring placed within the tubular portion *C*.

F are the vertical slots in the tubular part *C* of the lever and *E* is a pin which passing transversely through the said slots *F* and through the main lever rod *B* within the said tubular portion *C* securely holds the parts together. The part *C* may be pressed down over the main rod *B* until the tops of the slots *F* come in contact with the pin *E* and when the part *C* is released the spring *D* within the tubular portion *C* expands and throws the tubular portion *C* upward until the bottoms of the slots *F* reach the pin *E*. When the machine is in operation, spinning the thread or twine *a*—, the lever projects above the

thread —a—, the thread —a— holding it in its vertical position as shown in the figures.

—d— is an ordinary stud for the lever.

—e— is a set screw to fasten the lever to 5 stud —d—.

—f— is bracket to hold the stud in position.

When the thread or strand breaks the lever is drawn down by cord —h— as shown in 10 Figs. 3 and 4 and following the arc —c— takes the position shown by dotted lines —c— in Fig. 2. When the thread or strand is tied the operative presses the tubular portion C of the lever down over the main portion B until 15 the top and bottom of the tubular portion arrive at the positions shown by dotted lines —b— in Fig. 2 in which position the top of the tubular portion of the lever is lower than the thread or strand —a— and may be passed under the same and to the opposite side thereof 20 and the operator then withdrawing his hand the spring D presses the tubular portion C up above the strand —a— as shown, in the drawings and the tension on the cord —h— 25 holds the lever in contact with the strand —a—, and keeps the cord —h— taut and thereby holds the belt shifter in the position shown in Fig. 3, that is, on the fixed pulley. As soon as the thread —a— breaks the lever

swings down into the position shown in dotted lines in Fig. 2, permitting the spring —n— to throw the upper end of the belt shifter to the right as shown in Fig. 3 so as to throw the belt off.

I claim—

1. In a stop motion for a spinning jenny, the combination with a belt shipping mechanism, of a cord connected therewith, a swinging lever B to which the other end of the cord is fastened, the tubular portion or sleeve 40 —C— provided with slots —F—, the pin —E—, and the spring D in the sleeve C, substantially as and for the purposes specified.

2. In a stop motion for a spinning jenny, the combination with a belt shipping mechanism, of a swinging lever adapted to rest against the thread being spun, a cord connecting said lever with the belt shipping mechanism, said lever having a sliding part, a spring for pressing said sliding part upward and 45 means for limiting the upward movement of said sliding part, all constructed substantially as described and set forth and for the purposes specified.

BENJAMIN BODELL.
